UNITED STATES PATENT OFFICE.

JOHN RATZER, OF RIDGEWOOD, NEW JERSEY.

FIRE-ESCAPE APPARATUS.

Application filed July 30, 1925. Serial No. 46,940.

The invention relates to a fire escape apparatus of the portable type adapted to be placed near and kept in readiness at a window or other opening so that the occupant of the room or other confined or blocked space may escape thereby to the ground or elsewhere in case of necessity.

The object of the invention is to produce an improved and simplified fire escape apparatus of the above type so that the person using it may let himself down safely and quickly from the upper to the lower level without any other effort on his part than grasping a rope or cord firmly and releasing a brake. To this end one feature of the invention is the provision of means for exerting a frictional drag or retarding action on the rope as the weight of the person causes it to descend with him, thereby letting him down safely and yet sufficiently fast. Another feature of the invention is the provision of an improved brake means within the control of the user of the apparatus whereby the speed of his descent may be still further regulated. The brake means also acts to hold the rope stationary, so that the person who is to use the apparatus may impose his whole weight on the rope before it starts to descend by his releasing the brake. Thus the descent of the rope and the speed of descent are entirely under the control of the person using the apparatus. The invention is more fully described hereinafter and is particularly pointed out in the appended claims.

The preferred form of the invention is illustrated in the accompanying drawing, in which:

Fig. 1 is a side elevation, partly broken away, of the improved fire escape apparatus;

Fig. 2 is a plan of the parts shown in Fig. 1;

Fig. 3 is a section taken along the line 3—3 of Fig. 1;

Fig. 4 is an enlarged section taken along the line 4—4 of Fig. 3, looking in the direction of the arrows, and

Fig. 5 is a section taken along the line 5—5 of Fig. 1.

The improved fire escape apparatus as illustrated in the drawings comprises an endless rope or cord 6 in the form of an elongated loop long enough to reach from the room in which the apparatus is located to the ground or other landing place. At

the upper end of the loop the rope passes through and is slidably supported in an inverted U-shaped tube 7 the middle section of which is looped upon itself once to form a single spiral 8 which exerts a frictional drag or retarding action on the rope as the weight of the person causes either section 9 or 10 to descend. In this connection it will be understood that the apparatus is so constructed that the person using it may grasp and cling to either section 9 or 10 of the rope 6, the spiral section 8 of the rope supporting tube 7 functioning the same in both directions of travel of the rope to prevent a too rapid descent.

The apparatus as a whole may be suspended by means of a hook 12 to a support located conveniently to the window or other opening from which the escape is to be effected. The hook 12 is swivelly connected at its lower end with the inverted U-shaped member 14, the downwardly projecting sides of which embrace the upwardly extending legs 15 of a clamp 16. It is thus seen that the swivel connection between the hook 12 and the member 14, and the pivotal connection between the member 14 and the legs 15 of the clamp 16, serve as a universal mounting for the fire escape apparatus. The clamp 16 serves to hold together the adjacent upper sections 18 and 19 of the spiral loop 8.

In order that neither section 9 or 10 of the rope 6 may descend under the weight of the person who grasps it until the person has fully placed himself in readiness for descent, I provide a brake device, generally indicated at 20, the operation of which is conveniently controlled by the user of the apparatus by means of the cord 21. The brake device 20 comprises two cylindrical brake members or plungers 22 and 24 which are slidably received in the hub-like bosses 25 extending inwardly from the collars 26 which embrace the downwardly projecting sections 27 of the tube 7. The collars 26 are preferably held together by the cross-piece 28. The outer end of each plunger 22 and 24 is grooved vertically in conformity with the cylindrical shape of the rope 6 so as to have a proper braking engagement therewith. The plungers are forced into engagement with the sections 9 and 10 of the rope 6 and disengaged therefrom by means of the lever 30 to the outer end of which the cord 21 is attached.

The inner end of the lever 30 is pivotally mounted on a stud 31 fixed in the cross-piece 28. The inner end or head of the lever 30 is provided with the laterally extending arms 32 and 33 which are pivotally connected by the links 34 with the inner ends of the plungers 22 and 24, respectively. A contractile spring 35, one end of which is attached to the lever 30 and the other end of which is attached to the tube 7, serves to turn the lever in a counter-clockwise direction and thereby force the plungers 22 and 24 into braking engagement with the sections 9 and 10 of the rope. The pressure with which the spring 35 forces the plungers 22 and 24 against the rope may be regulated by shifting the lower end of the spring from one to another of the holes 36 in the lever 30.

20 The improved fire escape apparatus as described above may be kept in readiness in a convenient place in any preferred manner. When it is desired to use the apparatus the hook 12 is inserted in the eye or hook provided for that purpose and the sections 9 and 10 of the rope 6 are let down out of the window or other opening. The person using the apparatus then grasps either of the sections 9 and 10 and entrusts his weight fully thereto after which he may pull down on the cord 21 and release the brake 20. Thereupon the weight of the person causes the rope 6 to travel through the tube 7, the spiral section 8 thereof exerting in most instances the proper amount of frictional retardation on the section of the rope to which the person is clinging to cause the descent to be made safely. If the person finds that the descent is too rapid for his comfort he may ease up on the cord 21 slightly, thereby permitting the plungers 22 and 24 to move into a light braking engagement with the rope. When the person first entrusts himself to the apparatus it is de-

sirable that he take the cord 21 in his hand 45 before grasping either section 9 or 10 of the rope so as not to release the section of the rope to which he is clinging when he pulls down on the cord 21.

What I claim as my invention and desire 50 to secure by Letters Patent, is:

1. A fire escape apparatus comprising, a rope, a tube having a spiral section in which the rope is supported with a frictional drag, and a brake device for normally holding the 55 rope against movement consisting of a plunger slidably mounted to move into and out of engagement with the rope, a lever for actuating the plunger, a spring connected with the lever for normally holding the 60 plunger against the rope, and a cord by which the user of the apparatus may operate the lever to disengage the plunger from the rope.

2. A fire escape apparatus comprising, an 65 endless rope, an inverted U-shaped tube in which the rope is slidably supported, the middle section of said tube being looped upon itself to form a spiral to exert a frictional drag upon the rope as it moves 70 through the tube, a collar mounted on each downturned leg of the tube, a cross-piece connecting the two collars, and a brake device comprising two plungers slidably mounted in the inner sides of the collars, 75 a lever pivotally mounted on the cross-piece, connections between the lever and the plungers, a spring connected with the lever for holding the plungers in braking engagement with the rope, and a cord connected 80 with the lever and arranged to be under the control of the user of the apparatus to operate the brake to disengage the plungers from the rope.

In testimony whereof I hereunto affix my 85 signature.

JOHN RATZER.
